Primary Examiner — Kevin Rudzinski(74) *Attorney, Agent, or Firm* — Bacon & Thomas, PLLC**(57) CLAIM**

The ornamental design for a gas lighter, as shown and described.

DESCRIPTION

FIG. 1 is a perspective view of a gas lighter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are included for the purpose of illustrating environmental structures and form no part of the claimed design.
